UNITED STATES PATENT OFFICE.

EUGENE R. WEBER, OF ROCHESTER, NEW YORK, ASSIGNOR TO SARGEANT & GREEN-LEAF INC., OF ROCHESTER, NEW YORK, A CORPORATION OF NEW YORK.

LOCK.

Application filed June 16, 1922. Serial No. 568,833.

To all whom it may concern:

Be it known that I, EUGENE R. WEBER, of Rochester, in the county of Monroe and State of New York, have invented certain new and useful Improvements in Locks; and I do hereby declare the following to be a full, clear, and exact description of the same, reference being had to the accompanying drawings, forming a part of this specification, and to the reference numerals marked thereon.

This invention relates to locks and more particularly to the variety adapted for securing relatively small doors or other cover means, having as one of its objects the provision of a simple, compact device comprising comparatively few parts for effectively securing a door or other cover in position. Another object is to provide a lock of this character having a casing which is itself adapted to serve also as a door, for use with relatively small closures or containers, such, for example, as pay telephones, vending machines and the like. To these and other ends the invention resides in certain improvements and combinations of parts all as will hereinafter be more fully described, the novel features being pointed out in the claims at the end of the specification.

In the drawings:

Figure 1 is an exterior view of a portion of a closure wall having a door and lock embodying the present invention applied thereto with the parts in locked position;

Figure 2 is a similar view with the parts in unlocked position;

Figure 3 is a view of the lock with the door portion removed showing the parts in locked position;

Figure 4 is a similar view but showing the parts in unlocked position;

Figure 5 is an enlarged view similar to Figure 3 with the bolt member removed;

Figure 6 is a sectional view on the line

45 6^a—6^a of Figure 1;

Figure 7 is a sectional view on the line 7^a—7^a of Figure 2;

Figure 8 is a sectional view substantially on the line 8^a—8^a of Figure 4.

50 Similar reference numerals throughout the several views indicate the same parts.

The invention is shown in the present instance as applied by way of illustration to a

cover or door for the opening in the box or cabinet of a pay telephone through which 55 access is had to the deposited money. This, however, is merely one adaptation in which the invention has been found particularly useful and the latter is of course applicable to a wide variety of other uses. Referring 60 more particularly to the drawings, there is shown at 10, Figure 1, a portion of the wall of a telephone closure or box having an opening 11 therein through which the hand may be passed to remove the deposited 65 money. This opening is in the present instance of substantially rectangular shape and the closure wall is inwardly offset around the opening to form a seat 12, Figure 6, on the outside of the wall for the 70 reception of the cover or door.

The door is in the present instance in the form of a plate 13 of a size and shape adapted to fit snugly in the marginal seat 12 about the closure opening and this door, as 75 already indicated, serves as the forward wall of the casing of the lock. The rear wall of the casing is formed by a plate 14, preferably of the shape or outline best shown in Figure 5, the corners of the plate 80 being turned forwardly, as at 15 toward the front casing wall or door 13 and then extended as at 16 parallel with and secured to the latter in any suitable manner, as by spot welding at 17, Figure 1. The rear wall 14 85 is smaller in outline than the opening 11 so as to freely enter the latter and may in fact have its corner portions terminated just short of the sides of the door to abut the edges of opening 11 and assist in locating the door in its seat 12. The front and rear casing walls are thus in parallel spaced relation with each other and are secured in such relation by suitable means such as supporting elements or rivets 18. The operating parts of the lock are supported and enclosed between the front and rear walls 90 of the casing.

The operating parts of the lock comprise, preferably, a substantially disk-shaped bolt member, or plate, 19, lying against the rear side of the door 13. This member preferably has the shape in outline best shown in Figure 3. That is to say, its periphery is turned rearwardly or inwardly of the opening 11, as at 20 and spaced portions 105 21

thereof are projected radially beyond the circular portion 20 parallel with the casing wall. Member 19 has a plurality of arcuate slotted portions 22 concentric with the center of the lock, each of which embraces one of the supporting and spacing elements or rivets 18, so that the member is supported and guided for limited rotary movement between the casing walls. In one position 10 of rotation of the member, as shown in Figures 2 and 4, its outline is, generally speaking, coincident with or within the general outline of the rear casing wall 14, so that in this, the unlocked position, the member 15 is adapted to pass through the opening 11 in the closure wall. Upon rotation of bolt member 19, however, to the locked position shown in Figures 1, 3 and 6 the bolt portions 21 are projected beyond the general 20 outline of the rear casing wall and the edges of the opening 19 in the closure for engagement with the side of the closure wall opposite the door, for locking the latter in place. The bolt member may, of course, 25 have other shapes, that shown in the present instance having the advantage of being compact and of securely holding the door at each of its four sides. Tumbler and fence means are provided for controlling the bolt member 19 and these, with the means for 30 operating the tumbler means and rotating the bolt member, are described below.

The tumbler means comprises one or more plates of the shape shown at 23, Figure 5. 35 Opposing sets of three tumblers each are employed in the present embodiment. Each of these plates is provided with slotted portions 24 slidably embracing a pair of the spacing elements 18 so as to have a limited 40 linear movement. Each is arcuately gated or slotted as at 25 to receive a fence and has also a sweep shoulder 26 extending adjacent one side of the center of the lock for cooperation with a key. A spring 27 fixed at 45 one end to the rear casing wall 14 and at the other to the tumbler, tends to move the latter to carry its slot 25 out of registry with the fence and its shoulder 26 to position for engagement by the corresponding 50 step of the key. The bolt member carries a pair of stubs or fences 28, one for each set of tumblers. The present key as indicated at 55 29 is of the flat variety although any other suitable form might be used, and has steps on both edges for cooperation simultaneously with both sets of tumblers and it is inserted through a keyhole 30 in the door of the shape show in Figure 1. The positions of the key when first inserted in the lock and 60 after movement to unlock the door are shown in dotted lines in Figures 1 and 2 respectively, and it is to be noted that the keyhole in the door is of such a shape as to limit the rotation of the key to an angular 65 movement of approximately 90 degrees.

Bolt member 19 is also formed with a keyhole 31 opposite the keyhole 30 in the door and preferably having the shape shown in Figure 3. This keyhole is preferably formed in a steel escutcheon 32 carried by 70 the member 19 and it is to be noted that the sides of this keyhole extend at an angle of substantially 45 degrees with each other, so that the key after insertion may be rotated to an angle of 45 degrees before engaging the bolt member. During this first part of the movement the key operates or slides the tumblers on their guides to register the tumbler slots with the fences and, when this is accomplished, comes into engagement with 75 the bolt member and rotates the latter through an angle of 45 degrees to the position shown in Figure 4, or in other words from locked to unlocked position. During the latter half of the key movement, of 80 course, the fences 28 are moved in the slots 25 of the tumblers, so that the tumblers are retained in adjusted position. When the key has thus been turned through an angle of 90 degrees to bring the parts to the position shown in Figure 4, the peripheral bolt portions 21 of member 19 are disposed to clear the sides of the closure opening and the combined door and lock may then be removed as a whole from the opening to afford 85 access to the latter. Upon replacement of the lock and door in position to close the opening, the key is rotated back to initial 90 position, thereby rotating the bolt member through an angle of 45 degrees to the initial position shown in Figure 1. When the fences have cleared the tumbler slots the tumblers are returned by the spring means described to the position for holding the bolt member in locked position. The key 100 may then be removed leaving the door securely locked. The key bit is preferably recessed as at 33, Figure 8, and the keyhole 30 in the door correspondingly shaped to 105 retain the key in the lock during operations and permit removal only when the key is in initial or locked position.

The operation of the device has been fully described in connection with the above explanation of the construction. It is apparent from the description and drawings that the lock is simple and compact in construction, comprising comparatively few parts which are of a character permitting manufacture at a relatively low cost. In addition to the character and compact arrangement of the lock parts themselves, the combination of the same with the door as a part of the lock casing enhances the simplicity, compactness and economy of the device. The engagement of the closure wall by the bolt member at a plurality of points insures the secure holding of the door against unauthorized opening, and obviates the need of keeper means for the bolt, as 110 115 120 125 130

well as the need of hinges for the door, which is conveniently removed bodily and replaced in the manner described.

I claim as my invention:

- 5 1. In a device of the class described, the combination with a closure for an opening, of a member movably carried thereby having a plurality of peripherally spaced bolting portions adapted by the movement of
10 the member to be projected beyond and withdrawn within the outline of the opening to be closed, devices for holding said member with said portions in projected bolting position, and means for releasing
15 the member from said devices and moving the same to withdraw said portions to unbolting position.

2. In a device of the class described, the combination with a detachable closure for
20 an opening, of a member rotarily carried thereby having a plurality of peripherally spaced bolting portions adapted by the rotation of said member to be projected beyond and withdrawn within the outline of
25 the opening to be closed, devices for holding said member with said portions in projected bolting position and means for releasing the member from said devices and rotating the same to withdraw said portions to unbolting position.

3. In a device of the class described, the combination with a closure larger in size than the opening to be closed thereby, of a member rotarily carried thereby having a plurality of peripherally spaced bolting portions adapted by the rotation of said member to be projected beyond and withdrawn within the outlines of said opening for engaging the sides thereof opposite said
35 closure, devices for holding said member with said portions in projected bolting position, and means for releasing the member from said devices and rotating the same to withdraw said portions to unbolting position.

4. A lock comprising a rotary member having a plurality of peripherally spaced bolting portions, devices for holding the member in locking position, and means for
40 releasing the member from said holding devices and rotating the same to unlocking position.

5. A lock comprising a substantially circular member supported for rotation in its own plane and provided with a plurality of circumferentially spaced bolting portions, a relatively movable tumbler and fence one of which parts is connected with

said member, and key means for operating the movable one of said parts and for rotating said member to unlocking position.

6. A lock comprising a substantially circular plate supported for rotation in its own plane and provided with a plurality of peripherally spaced bolting portions, fence
65 means on the plate, tumbler means, and key means for adjusting the tumbler means and rotating the plate.

7. In a lock, a casing comprising front and rear walls and a plurality of elements supporting the same in spaced relation, a disk-shaped member having arcuate slotted portions embracing said elements to rotarily support said member between said walls, said member being disposed within the outlines of said rear wall in unlocked position and having peripherally spaced bolting portions adapted to be projected beyond the rear wall by rotation of the member to locked position, fence means connected to
75 said member, tumbler means on the casing, and key means for operating the tumbler means and rotating said member.

8. The combination with a closure having a wall provided with an opening therein, of a door for said opening larger in size than the latter, a member rotarily supported on the door and adapted in one position of rotation to enter said opening, a plurality of bolting portions on said member adapted
85 to be projected by rotation of the member to another position to extend beyond the sides of the opening for engagement with the side of the closure wall opposite the door, cooperating tumbler and fence means
90 for holding the member in said other position, and means for operating the tumbler means and rotating said member.

9. The combination with a closure having a wall provided with an opening therein, of a combined door and lock for said opening comprising a casing having a front wall larger in size than the opening to close the same and a rear wall adapted to pass through the opening, a member rotarily supported between said casing walls adapted in one rotary position to pass through said opening and in another rotary position to engage the sides of the latter on the side of the closure wall opposite the
100 door to hold the latter in position, tumbler and fence means in the casing for holding the member in said other position, and means for operating the tumbler means and rotating said member.

EUGENE R. WEBER.
